BALL POINT PEN

Clarence D. Zierhut, Granada Hills, Calif., and John H. Wasson, Madison, Wis., assignors to Paper Mate Manufacturing Company, Santa Monica, Calif., a corporation of Delaware

Filed Feb. 10, 1965, Ser. No. 83,762

Term of patent 14 years

(Cl. D74—17)

FIG. 1.

FIG. 2.

FIG. 3.

FIG. 1 is a side elevational view of a ball point pen showing our new design, the opposite side being substantially the same in appearance;

FIG. 2 is a front elevational view thereof;

FIG. 3 is an enlarged fragmentary front elevational view of the lower section of the ball point pen shown in FIGS. 1 and 2, this view showing the new and ornamental effect obtained by the combination of an opaque axial portion with a virtually transparent outer portion in such lower section.

The essential features of our design reside in the portions shown in solid lines on the drawing.

We claim:

The ornamental design for a ball point pen, as shown and described.
